CLAIM

The ornamental design for a reagent receptacle, as shown and described.

DESCRIPTION

FIG. 1 is a front perspective view of a reagent receptacle according to our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines illustrate unclaimed environmental structure and form no part of the claimed design. The oblique shade lines shown in the drawings indicate a transparent or translucent surface.
